UNITED STATES PATENT OFFICE.

ELI OPPENHEIM, OF BALTIMORE, MARYLAND, ASSIGNOR TO OPPENHEIM, OBERNDORF & CO. INC., OF BALTIMORE, MARYLAND, A CORPORATION OF MARYLAND.

COMBINATION-GARMENT.

1,254,630.

Specification of Letters Patent. Patented Jan. 22, 1918.

Application filed May 1, 1916. Serial No. 94,527.

To all whom it may concern:

Be it known that I, ELI OPPENHEIM, a citizen of the United States, residing at Baltimore, in the State of Maryland, have 5 invented certain new and useful Improvements in Combination-Garments, of which the following is a specification.

My invention relates to an improved combination garment or union suit. 10 A union suit undergarment can be made much more attractive; of greater utility and more comfortable to the wearer by providing the shirt or body portion of a fine material that will be soothing to the tender 15 skin of the wearer's body, and, constructing the drawers portion of the garment of a more durable material. I have found that in a garment of this character it is desirable to relieve the finer and sometimes delicate 20 body-material of undue strains during some movements, such as when the wearer is stooping or bending over, and

I have further found that greater comfort to the wearer can be obtained by providing 25 ventilation for the skin across the front of the garment at, or adjacent to, the waist.

The objects therefore of my invention are to provide an improved garment embodying the above features and which will present an 30 attractive appearance, particularly in cases where the shirt or body portion is exposed to view, and at the same time produce a garment that will provide comfort and ease to the wearer.

35 The invention is illustrated in the accompanying drawing in which,—

Figure 1, shows the improved garment in front view.

Fig. 2, illustrates a portion of the rear of 40 the garment where the body and drawers materials are connected by elastic webbing, and

Fig. 3, shows a fragment of the garment in side elevation to illustrate the two cross-wise 45 insert pieces which connect the front and back of the body material with the front and back respectively of the drawers material.

In carrying out the invention, as shown in the drawing, the body portion 5, of the garment is made preferably of a silk or other 50 attractive or dressy material, and in constructing this body portion I may, if desired, make the front 6, thereof of a greater length than the rear 7,—the advantage of 55 which will presently be explained.

The body portion 5, is provided with a placket 8, down the front with fastenings 9, to secure the placket flaps together. By preference, the front placket of the body has a strip or extension 10, that projects below 60 the lower edge 11, of the body front 6, also for a purpose which will presently be explained.

The drawers portion 12, of the garment is preferably made of ordinary material and 65 also has a front portion 13, and a rear portion 14. The front portion 13, of the drawers is, in the present instance, shorter or of less height than the rear portion 14, so that, in the form illustrated, the lower edge of the 70 front 6, of the body terminates in a horizontal plane below the upper edge of the rear portion 14, of the drawers.

The front 13, of the drawers portion is provided with a placket 15, which is in alignment with the extension 10, of the body placket, while the rear portion 14, of the drawers is provided with a posterior flap 16, whose upper edge 17, terminates in a horizontal plane above the upper edge 18, of the 80 front of the drawers.

The upper rear edge of the drawers and the lower rear edge of the body are united horizontally or across the back of the garment by a strip of elastic material 19, whereby to provide for vertical strains that occur 85 at the rear, and to relieve the finer body material of those rear strains.

At the front of the garment and extending crosswise thereof I provide two strips 90 20, of a non-elastic, open-mesh ventilating fabric. These two strips of fabric extend from the side edges of the garment toward the placket extension 10, and in the present instance they connect the shorter front edge 95 18, of the drawers with the longer and lower front edge 11, of the body.

By means of the construction above described I provide a garment, the body portion of which has a comparatively long 100 front and a shorter back, which long front results in a concealment of the front ventilating strip 20, by the upper waist-edge of the wearer's trousers when the garment is worn by a man, and the shorter back of 105 which enables the posterior rear flap 16, of the drawers to extend far enough up the back to provide ample length of rear opening.

By providing the placket extension or 110

strip 10, on the body front and allowing the same to extend across the plane of the two strips 20, I provide a durable and inelastic connection directly between the body front and drawers so that the fabric strips 20, are relieved of strains that might possibly occur at the front.

Having described my invention what I claim is,—

- 10 1. A combination garment comprising a body portion and a drawers portion both having a front placket,—the material of the body and the material of the drawers being separated at the front of the garment in a direction crosswise of the placket, and said garment having strips of ventilating material at the front and at opposite sides of the placket which strips connect the body and drawers portion.
- 20 2. A combination garment comprising a body portion and a drawers portion the body portion having a front placket with an extension that projects below the body and the drawers having a front placket which registers with the body-placket extension,—the material of the body and the material of the drawers being separated at the front of the garment in a direction crosswise and at opposite sides of the placket extension and strips of ventilating material at the front of the garment at opposite sides of the placket extension said strips connecting the body and drawers portion.

Copies of this patent may be obtained for five cents each, by addressing the "Commissioner of Patents, Washington, D. C."

3. A combination garment comprising a body portion having a front and a drawers portion having a front said body and drawers fronts being connected by strips of non-elastic open-mesh ventilating material and the garment having a back with a posterior flap.

4. A combination garment having a body portion and a drawers portion the body and drawers being connected at the front by strips of ventilating material and said body and drawers being connected at the back by an elastic material and at the rear said garment having a posterior flap that terminates at the elastic material connection.

5. A combination garment having a body portion and a drawers portion the body and drawers being connected at the front by strips of non-elastic ventilating material and said body and drawers being connected at the back by an elastic material the strips of ventilating material at the front being lower on the garment than the elastic material connection at the rear, and at the rear said garment having a posterior flap that terminates at the elastic material connection.

In testimony whereof I affix my signature in the presence of two witnesses.

ELI OPPENHEIM.
